BENJAMIN S. WHITEHEAD.

BY *Fred C. Frantz, ATT'Y.*

UNITED STATES PATENT OFFICE.

BENJAMIN S. WHITEHEAD, OF NEWARK, NEW JERSEY.

DESIGN FOR A BADGE.

SPECIFICATION forming part of Design No. 23,817, dated November 27, 1894.

Application filed June 7, 1894. Serial No. 513,830. Term of patent 7 years.

To all whom it may concern:

Be it known that I, BENJAMIN S. WHITEHEAD, a citizen of the United States, residing at Newark, in the county of Essex and State 5 of New Jersey, have invented and produced a new and original Design for Badges, of which the following is a full, clear, and exact description of the invention, reference being had to the accompanying drawing, and letters of reference marked thereon, which form part of this specification.

In the drawing the figure presented illustrates a front view of the badge embodying the leading features of my new design.

15 The novel feature of said design for a badge is, first, the straight and long body ribbon; next, the short ribbon forming a pendant from the upper edge of said long body ribbon; and finally the circular medallion having a bead-like ring-shaped edge, on the end 20 of said short ribbon.

In the drawing, α designates the long body-ribbon having the straight edges α' . Forming a pendant from the upper edge α^2 of the 25 long body-ribbon α is the short pendant-rib-

bon b , having the straight sides b' , the rounded points b^2 , forming the folds b^3 in said ribbon.

An additional feature in the design is the medallion consisting of a medallion plate c , which is of the shape of a circle in outline, 30 and is bounded by a bead-like ring c' forming a frame for the medallion.

The essential part of the design consists of the general outline and configuration of the several parts as follows: first, the straight 35 and long ribbon; second, the short pendant ribbon; and lastly the medallion at the end of the pendant ribbon, all combined to produce the new and original design for a badge as described hereinabove. 40

What I claim is—

The design for a badge, substantially as described and shown.

In testimony that I claim the invention set forth above I have hereunto set my hand this 50 6th day of June, 1894.

BENJAMIN S. WHITEHEAD.
